UNITED STATES PATENT OFFICE

2,542,132

ELECTRIC SWITCH

William S. Goertzen, Newton, Kans.

Application April 15, 1947, Serial No. 741,451

1 Claim. (Cl. 200—52)

1

My invention relates to an electric switch and has for its principal object to break an electric circuit as rocked from its circuit closing position, as a safety result when applied to a steam boiler or the like.

A further object of the invention is to provide a switch that will break the circuit by the vertical position of a structure containing the switch and likewise close the circuit when the structure is abnormally inclined for the result of illumination.

A still further object of my invention is to provide a switch for an electric circuit that will function under gravity control to close the circuit or break the same.

A still further object of my invention is to provide a switch whose elements are of rigid material to make and break an electric circuit whereby the negative or positive side of the circuit has a pendently carried element that will swing to and from engagement with the other pole as controlled by gravity.

These and other objects will hereinafter be more fully explained, reference being had to the accompanying drawings forming a part of this specification, in which like characters will apply to like parts in the different views.

Referring to the drawings:

Fig. 1 represents the switch positioned in a fishing bob, partly in section.

Fig. 2 is an enlarged view of the switch showing its circuit closing position, parts removed for convenience of illustration.

Fig. 3 illustrates one position of the switch mechanism to break the circuit.

Fig. 4 represents the position of the switch to break the circuit when the device is inverted.

Fig. 5 shows the adaption of the switch as a safety control.

The invention herein disclosed consists of two applications of a switch, one of which consists of a tubular body 1 functioning as a housing. Said housing has a lining 2 of insulation material that extends from the upper end of the housing downward to a spaced distance from the lower end thereof, the terminal end of the lining forming a shoulder and a fulcrum point as at A on which a cylindrical elongated bob 3 will rock as carried by links 4 and 5, the links coacting with the bob for the other side of the circuit, the major length of the bob being adjacent the links so that the minor portion will be rocked from engagement with the shell as the housing reaches a horizontal position as shown in Fig. 3. Link 5 is integrally joined to a helical spring 6 to seat on a head 7 of insulation material (the spring purpose later

2

described). Said link 4 is rockably connected to the upper end of the said bob by ball and socket engagement by which means the bob is free to rock to and from engagement with the shell of the container, and furthermore the said links being elongated is means for collapsation thereof when the housing is inverted as shown in Fig. 4, when in which case the circuit is broken when the body of the bob rests upon the insulated lining.

The said housing 1 has a head 1' threadedly engaging on its lower end thereof as shown in Figs. 1 and 2, while the upper end is externally threaded a short distance downward to engage with the internal threads at the lower end of a tube 8, said tube functioning as a container for a battery 9 that seats on the upper extremity of the helical spring 6 which is the connection for one end of the battery. The other end of the battery is in connection with the stem of a lamp 10, the stem threadedly engaging in a metallic socket 11 that fits snugly in the upper end of the battery tube. The upper end of the tube has a transparent disc 12 suitably secured therein fluid tight as at B, and against which the upper end of the lamp socket will engage.

Integrally joined to the upper end of the battery tube 8 is an annular flange 13 outwardly extending to seat on an annular gasket 14 and being bound thereto by a collar 15 that is internally threaded to engage with the threaded portion of the tube adjacent last said flange. The said flange 13 has a V-shaped bridge 16 diametrically crossing the same and integrally joined thereto, the bridge being apertured at its apex thereof through which a fish line 17 will extend, the line being secured at a predetermined point therealong to the bridge apex to accommodate for the depth of a hook 18 as secured to the downwardly extending free end of the line. The tubular battery container 8 together with the switch container are insertible in a bore 19 axially positioned in a fish line float 20 as shown in Fig. 1, and being secured therein by snug engagement of the said collar 15 in its enlarged portion of the bore 19, and being so arranged as above described, the containers are removable from the bore of the tubular body of the float 20. Said float is elongated and formed so that it will retain itself in a vertical position when placed in a body of water, in which case, the circuit is broken, however when a fish pulls the line by a bite on the hook, the float will rock from a vertical position to close a circuit for the lamp. An upper portion of the float and including the lamp is exposed

above the water and discernible when the lamp is illuminated, whereby when the fish is caught or when the same is biting on the line will actuate the lamp to notify the fisherman, it being understood that the float of this character may be used at night or partially darkened days.

In Fig. 5 is shown the installation of a metallic bob 21 positioned within a spherical hollow float 22 that has an arm 23 radially extending and pivotedly connected as at C to another arm 24, the latter being joined, for example, to the wall of a steam boiler, its water column, or the like (the boiler or column not being shown in the drawings). In either event, the spherical body will function as a float, the rocking of which is controlled by the rise and fall of water contained in the boiler, the purpose of which being to make or break an electric circuit as a safety device to extinguish the burning of gaseous fuel used as a boiling means for the water contained in the boiler. The circuit is broken when the water reaches the low danger level, at which point, the spherical float will take its position as shown by dotted lines D in Fig. 5, and in which position, the bob by gravity actuation automatically moves from contact with the shell of the float thus breaking the circuit and permitting the closing of a gaseous fuel valve through the medium of a spring that is released at the time of breaking the electric circuit. It will be understood that the said valve is provided with an electric motor that over powers the spring tension when the current is on. The valve, its motor, a gas burner, and the boiler are of conventional types and well known to such line of service, all of which have been omitted from the drawings, but the electric circuit control for such service may be arranged as follows:

The link 25 is connected to a rigid extension 26 that is fixed in any suitable manner to said float and its arm 23, said extension being insulated by a tube 27 of insulation material, while the extension is connected to an electric feed line 28 as a source of electric power and being one side of the circuit. The float through its connection with the boiler or column constitutes the other side of the circuit, therefore the said elongated bob is the medium or connecting link to close the circuit when it moves in contact with the shell of the float as shown by whole lines in Fig. 5, and by reason of a low water danger line the said float will recede downwardly as above described, whereby the electric circuit is broken, killing the motor so that the spring tensioned valve thereof is free to cut off the fuel supply to avoid boiler explosion.

While I have shown a specific form for the switch bob and its containers, I do not wish to be restricted to such alone as the same may be varied to meet conditions required for a perfect performance of the principle herein set forth, and the switch as gravity actuated may be applied to other purposes to restrict against emergencies or to supply a desired effect by making or breaking an electric circuit for producing an essential result, and such other modifications may be made as lie with the scope of the appended claim.

Having fully described my invention what I claim as new and desire to secure by Letters Patent is:

In an electric switch comprising an elongated tubular housing vertically positioned and being externally threaded on its lower end, a flanged head threadedly engaging said lower end, a circular head of insulation material secured on the upper end of the housing to close said end thereof, a lining of insulation material positioned in the housing, said lining extending from the insulation head and terminating a spaced distance from the flanged head of the housing, a U-shaped link structure extending inwardly from the insulation head, a link rockably connected to first said link structure, an elongated metallic bob and rockable connecting means for one end of said bob to the second said link, the other end of said bob serving as a switch when the same contacts the housing between the flanged head and adjacent end of the lining should the housing be rocked a predetermined angle from a vertical line and when rocked to a greater angle, the bob lies on the insulating lining as a safety means to break a circuit.

WILLIAM S. GOERTZEN.
